(74) Attorney, Agent, or Firm — Jeffrey Schox; Diana Lin

(57) **CLAIM**

The ornamental design for a robot, as shown and described.

DESCRIPTION

FIG. 1 is an isometric view, from the top right, of a first embodiment of the robot.

FIG. 2 is an isometric view, from the bottom left, of the first embodiment of the robot.

FIG. 3 is an elevation view from the front of the first embodiment of the robot.

FIG. 4 is an elevation view from the back of the first embodiment of the robot.

FIG. 5 is an elevation view from the right side of the first embodiment of the robot

FIG. 6 is an elevation view from the left side of the first embodiment of the robot.

FIG. 7 is a plan view from the top of the first embodiment of the robot; and,

FIG. 8 is a plan view from the bottom of the first embodiment of the robot.

Any broken lines are understood to illustrate portions of the robot only and form no part of the claimed design.

1 Claim, 4 Drawing Sheets(56)
